UNITED STATES PATENT OFFICE.

HAROLD B. PULLAR, OF DETROIT, MICHIGAN.

BUILDING MATERIAL.

Application filed December 26, 1925, Serial No. 77,709. Renewed May 24, 1928.

This invention relates to improvements in building material, and refers more particularly to lengths of building material which will be adaptable to numerous and varied uses, for instance, as siding for garages, warehouses, floors, freight cars and the like.

The building material of the present invention possesses certain inherent properties and characteristics, for instance flexibility to allow for proper expansion and contraction, rigidity to permit economical stacking, shipping and installation, and insulating properties to a high degree.

Briefly, the building material of the present invention comprises ordinary building board recessed in its body portion on both surfaces, said recesses being filled with a waterproofing mastic or compound such as asphalt and a filler. This building board may be of any length, convenient for installation, and may be of any width from say two inches up to twelve inches more or less, and may have a tongue and groove connection with adjacent building boards.

In the drawings, Fig. 1 is a face view showing a built-up wall utilizing lengths of building material of the present invention.

Fig. 2 is a cross sectional view taken on line 2—2 of Fig. 1.

Fig. 3 is a perspective view of one length of building material.

Referring more in detail to the drawings, each unit 1 comprises a central body portion 2 and end sections 3 and 4. The body portion 2 and end sections 3 and 4 may be made of wood, felt or molded fibre, metal or any other rigid, semi-rigid or flexible material as desired. The end sections 3 and 4 are of course, wider than the body portion, which latter is provided on both of its surfaces with a recess relative to the end sections. The thickness of the body portion 2 should preferably not exceed one-half the thickness of the completed building unit, and it is preferable that the integral structure comprising the body portion 2 and end sections 3 and 4 take a substantially I bar construction having the tongue 5 on one end section, and the corresponding groove 6 adapted to register therewith on the other end section. The recesses

on both surfaces of the body portion may be formed by removing a portion severed along the lines shown in Fig. 2, or the recesses may be formed integral at the time of formation of the body portion, in the case of felted or molded fibre or metal. After the skeleton construction comprising the body portion 2 and end sections 3 and 4 is formed, there is poured or otherwise formed in the recessed areas adjacent the surfaces of the body portion 2 a bituminous compound 7 such as pure asphalt or an asphaltic material having a melting point in excess of say 125° F. more or less. Any desirable filler such as sand, sawdust, cork or the like, may be mixed with the bituminous compound 7, if desired. This bituminous compound is preferably poured or formed in said recessed areas while in heated condition, and may have a surfacing 8 imbedded therein, or applied thereto, which may be for instance, fine sand, slate, stone or other granular substances. If the granular surfacing is not desired, a coating of talc or mica to prevent adhesion may be applied.

The thickness of the building board of the present invention may vary from one-fourth inch to two inches, more or less.

It will be obvious that the building board of the present invention embodies the aforementioned properties and characteristics in a manner which is very novel.

In Fig. 1, I have illustrated a vertical wall constructed by joining adjacent pieces of building board together. It is obvious of course, that the building board may be laid in any plane, for instance, horizontal or at an angle from the horizontal, if desired, for ornamental effect.

The building board of the present invention may be used for floors, if desired. It is acid and alkali proof, and has the advantage of durability and good wearing qualities. As a substitute for wood flooring, it has more resiliency, has insulating qualities, and is sanitary, and will outwear wood many times. Where it is used for floors, it is preferable to have a minimum of wood visible, and it may be advisable to have a coating of asphalt or asphaltic compound applied to the surface of the wood.

The building board of the present invention may be used for the side wall on refrigerator cars, thus utilizing its insulating properties.

5 I claim as my invention:

Building material including in combination, a supporting base comprising a body

portion and end sections connected thereto, and having a filling on a surface of the body portion of bituminous material, the end sections being provided with registering means by which they are adapted to be connected adjacent each other.

10 HAROLD B. PULLAR.
